UNITED STATES PATENT OFFICE

CLARENCE P. BYRNES, OF SEWICKLEY, PENNSYLVANIA, ASSIGNOR TO WINDOW GLASS MACHINE COMPANY, OF PITTSBURGH, PENNSYLVANIA, A CORPORATION OF NEW JERSEY

METHOD AND APPARATUS FOR THE MANUFACTURE OF SHEET GLASS

Original application filed March 2, 1920, Serial No. 362,844. Divided and this application filed July 5, 1924, Serial No. 724,255.

Figure 1 is a diagrammatic partial vertical section showing one form of apparatus for carrying out the invention; and

Figure 2 is a view at right angles to Figure 5 1, showing another form.

My invention relates to the manufacture of sheet glass, and its object is to increase the production and lower the cost of drawing glass in continuous sheet form over a bending 10 roller. To that end, the invention consists in continuously drawing a plurality of sheets from the same general bath of molten glass, each sheet rising in a general vertical direction and thence being bent into a general 15 horizontal direction over a bending roll or device, thus giving continuous multiple drawing.

In the drawings, referring to the form of Figure 1, 2 represents the end portion of a 20 tank furnace, which extends to the right of the figure. 3, 3 designate bending rolls, located in different vertical and horizontal planes, and over which the continuous sheets are bent, thence extending horizontally and 25 preferably passing through a flattening station and an annealing oven. These sheets are preferably drawn with thickened edge portions, which thickened edge portions are preferably engaged just above the meniscus by 30 friction brake devices, preferably in the form of stub rollers, engaging these thickened edges from opposite sides, as indicated at 4. The amount of friction or drag exerted by 35 these rollers may be adjusted in any suitable manner.

After passing the bending roller, the thickened edges are engaged by the end collars of upper and lower rollers 5, 5, which are preferably geared together outside of the enclosing tunnel 6, thereby imparting a drawing 40 action or pull to the continuous sheet. 7 indicates the heat supplied, which is directed upon the continuous sheet after passing the bending roll.

45 The numeral 8 designates water coolers arranged between the two sheets and at each side thereof, to impart the desired set or plasticity. The horizontal paths of the two continuous sheets are preferably separated by a 50 refractory roof 9, and heating and cooling

means may be supplied as desired in any parts of the draw.

In figure 2, I show another form in which the section of the tank extension is at right angles to the first view, the sheets being drawn horizontally in opposite directions at general right angles to the length of the tank. In this form, the horizontal paths of the continuous sheets, after bending, may be in the same horizontal plane, and a refractory partition 60 wall 9a may extend between the bending rollers, if desired. Similar parts are marked with similar numerals in both views, the letter "a" being added to similar parts in the second view. The bending rolls may be cooled 65 by air or water, or otherwise, as desired, and if desired, hot gases, steam or other fluids may be forced through perforations in the roll to keep the sheet further from its surface.

By such system, the amount of glass produced by a tank may be greatly increased, depending on the number of continuous sheets drawn simultaneously. Heretofore, each tank has been provided with one drawing extension or drawing tank, and one continuous sheet has been drawn therefrom, but by drawing sheets in different directions or stepping them vertically, one over the other, a plurality of sheets may be drawn from the same general bath system.

80 The advantages of the invention will be obvious to those skilled in the art. Heretofore, only one drawing apparatus of this type has been employed in connection with a tank furnace, on account of the difficulties connected with multiple drawings, where the glass is drawn first in a vertical direction, thence in a generally horizontal direction. By my improvement, the output is greatly increased 85 and the cost correspondingly reduced.

90 This application is a division of my co-pending application, Serial No. 362,844, filed March 2, 1920, for Manufacture of sheet glass.

I claim:

1. In an apparatus for simultaneously producing a plurality of sheets of glass, a horizontal leer, a series of conveyors for carrying the separate sheets in parallel horizontal planes through the leer, and means positioned between each pair of conveyors for 100

protecting the lower sheets from falling material.

- 8 2. In the drawing of sheet glass, the steps consisting of simultaneously drawing a plurality of sheets upwardly from a bath of glass, then bending the sheets and drawing them in different paths in a generally horizontal direction, one above the other, in the same heated leer structure, and protecting the lower sheet from falling material.
- 10 3. The process of producing sheet glass, consisting in providing a mass of molten glass, skimming the molten glass by drawing the surface therefrom in sheet form, and then drawing a sheet from the skimmed glass.
- 15 4. In sheet glass apparatus, means for containing a mass of molten glass, means for skimming the molten glass including means for drawing a sheet from the surface thereof, and means for drawing a commercial sheet from the glass that has been skimmed.
- 20

In testimony whereof I have hereunto set my hand.

CLARENCE P. BYRNES.
